UNITED STATES PATENT OFFICE

JULIUS A. SCHWANTES, OF WAUWATOSA, WISCONSIN, ASSIGNOR TO COLGATE-PALM-OLIVE-PEET COMPANY, OF CHICAGO, ILLINOIS, A CORPORATION OF DELAWARE

SOAP MANUFACTURE

Application filed June 28, 1928. Serial No. 288,951.

The invention relates to a method of producing shredded soap.

The general object of the invention is to improve upon the process set forth in my prior United States Patent No. 1,603,559, dated October 19, 1926, wherein soap shreds are formed by the mechanical breaking up of soap, in a semi-liquid or pastelike condition, into tiny shreds which are dried sufficiently to render them non-adhering. One of the objects of the present invention is to provide a process for producing an aerated, mechanically shredded soap product. While it is old to impregnate a body of molten soap with air by a crutching operation, as, for example in the United States patent to Ellis, No. 1,007,680, of November 7, 1911, where such crutching has been employed the soap is produced in a dried cake-like mass that necessitates subsequent breaking. By the present process the particle formation is effected mechanically just prior to the drying of the product. It has also been proposed to spray liquid soap by means of compressed air but such a process simply acts to disrupt the soap into small particles and does not bring about an intimate mixing of soap and air necessary to produce a truly aerated product, but produces dust-like particles. By the present process the soap in a frothy, pasty, thread-like condition is mechanically cut into tiny shreds which are subjected to the action of a suitable drying gas to evaporate the desired amount of moisture therefrom and cause the particles to become solidified into separate, non-adhering entities.

While the soap shreds produced as above described may be dried in various ways, I prefer to dry them by the well known countercurrent flow principal of drying semi-liquid substances, but to improve upon my aforementioned patent in this respect by causing the drying air to pass through the drying chamber under the action of a suction-producing device at the upper end of the chamber, whereby the finer particles of the product can be collected and the waste air be discharged in a clean condition, thus effecting a recovery of such of the finer particles as were previously wasted and also pre-

venting soap laden air from becoming a nuisance to the vicinity surrounding the plant.

The invention further consists in the method and steps of the method as hereinafter set forth and more particularly defined by claims at the conclusion hereof.

In the drawings Fig. 1 is an elevation view of apparatus embodying the invention, parts being broken away;

Fig. 2 is a detail sectional view taken on the line 2—2 of Fig. 1;

Fig. 3 is a detail sectional view through the shredder.

Referring to the drawings, the numeral 5 designates a steam-jacketed storage tank where the soap is kept in a liquid condition by heating it to a suitable temperature, as for example, 180 degrees Fahrenheit. The soap is introduced into this tank by a pipe 6 connected with a suitable source of supply.

The liquid soap is drawn off from the bottom of the tank by gravity and in addition by a pair of pumps 8 connected by pipe 7 with the tank 5 and arranged in multistage relation and driven by an electric motor 9 through a suitable variable transmission drive 10, including belts 11. The liquid soap is delivered under pressure by the pumps which control its rate of discharge to and through a discharge line 12 to an agitator 13 which is of the rotary type and may be a suitable centrifugal pump or beater.

Just before the soap enters the agitator 13 compressed air, from a compressor 14 driven in any suitable manner as by an electric motor and delivering to a receiver 15, is introduced into the line 12 by a pipe 16 connected with said receiver. The air pressure is sufficiently in excess of the soap pump delivery pressure to cause the air to enter the discharge line 12 in the proper quantity and proceed with the soap into the agitator or fluffer 13 where the soap is thoroughly whipped into a froth, the air pressure then being the same as the soap pump pressure. This frothy soap is discharged through a pipe 17 to a shredding apparatus 18. The shredding apparatus may be of the type shown in my prior United States Patent No. 1,581,664, wherein the liquid soap, under the

action of the pump discharge pressure and the centrifugal force set up in the soap by a rapidly rotating disc through which the soap is fed, is discharged therefrom and cut into fine shreds during its discharge by the action 5 of a disc rotating in the opposite direction from the first-named disc so that a further detailed showing is not deemed necessary here. However, the shredder drive has been 10 modified by the direct drive of shaft 20 by an electric motor 21, said shaft being connected to the shaft 22 associated with the first-named disc by gears 23, 24 and 25 and with the shaft 26 for the second disc by gears 15 27 and 28.

To insure the soap being maintained at the proper temperature the discharge pipe 17 is steam-jacketed and steam from a live-steam line 29 passes through jacketed portions 30 20 of this pipe and thence by way of pipe 31 to the jacket space 32 of the tank and the condensate is discharged through overflow pipe 33. Pipes 34 and 35 connect the line 29 with the soap pipe for blowing or cleaning it out 25 and pipe 35' is a pipe line for draining the soap from the supply tank, if necessary.

It will be noted that the various pipe lines above described are equipped with valves to control the flow of the liquids or fluids 30 within them.

The shredding apparatus 18 is located centrally in the upper portion of a large drying chamber 36, the upper part of the shredding apparatus and the feed pipes associated therewith being in a compartment 37, separate 35 from but extending into the drying chamber. A small propeller 38, mounted on the shaft 26, is used to direct air in the immediate vicinity of the shredder head downward 40 in order to keep the soap particles from collecting on parts of the shredder apparatus.

Air drawn into a chamber 39, past heating coils 40, is introduced into the lower conical part of the chamber 36 through ports 41. An 45 air-rotated member 42 is centrally mounted in the lower end of the chamber and is provided with wiper blades 43 moving adjacent the side walls at the lower end of the chamber to keep the port 41 clean. The air 50 is preferably heated to quite a high temperature, for example 260 degrees Fahrenheit, and as it ascends through the chamber 39 it comes into intimate drying contact with the small shredded particles of soap that are 55 being projected into the chamber by the shredding apparatus, with the result that these particles are rapidly transformed from an emulsive state into small dried particles of soap having minute air bubbles entrapped 60 therein, which particles gravitate to the bottom of the drying chamber where they are removed by a positively driven, revolving gate 44 which deposits them onto a conveyor 65 upon which they are cooled as they proceed through a cooling chamber 46 and are

then led to a place of storage or packaging.

The warm drying air is preferably caused to move upwardly by the action of a suction fan 47 connected by a conduit 48 with the upper end of a cyclone separator chamber 49 which connects by conduit 50 with the upper end of the drying chamber 39 and which has a valved outlet 51 for controlling the discharge of collected soap particles. By this arrangement any fine particles carried off by the drying air are deposited in the separator 49 from which they are recovered and thus the air delivered by the fan 47 to atmosphere is substantially clean.

What I claim as my invention is:

1. The method of making shredded soap which comprises beating a mixture of hot, semifluid soap and air, under pressure, into a frothy condition, delivering the mixture so formed to a shredder, shredding said soap while in its semifluid condition, and drying said shreds as non-adhering entities.

2. The method of making shredded soap which comprises beating a mixture of hot semifluid soap and air, under pressure, into a frothy condition, delivering the mixture so formed to a shredder, shredding said soap while in its semifluid condition and discharging it as shredded into a drying current of heated air.

3. The method of making shredded soap which comprises delivering soap in semifluid condition to a shredder, shredding the soap as it is discharged from the shredder, drying the shredded soap particles by downward descent in an upwardly moving current of heated air, and inducing a downward flow of the drying air adjacent the shredder to prevent deposition of soap particles thereon.

In testimony whereof, I affix my signature.
JULIUS A. SCHWANTES.
